UNITED STATES PATENT OFFICE

ERIC W. JOHNSON, OF NEWARK, NEW JERSEY

AUTOMATICALLY LOCKED RECEPTACLE AND CONTAINER

Application filed December 13, 1929. Serial No. 413,756.

This invention relates to automatically locked receptacles and containers for receiving milk bottles or other articles which are safe therein against unauthorized removal, said receptacles being particularly adapted to be located outside a house door in such relative position thereto that said door forms a closure for said receptacles and prevents their removal until said door is opened.

The main object of my invention is to provide a receptacle to be placed outside a house door which may receive delivered articles without necessitating opening the door, and yet which will safely retain such delivered articles against theft or removal from the outside.

Another object is to provide a receptacle of the character indicated which is readily placed in position at will and as easily removed.

A further object is to provide such a receptacle which is closed upon one side by the house door and simultaneously retained in position by the same.

Other objects and features of my invention will appear more fully in detail as this specification proceeds.

In the accompanying drawings forming part hereof:—

Fig. 1 is a view of a receptacle made according to my invention and placed in proper position for use outside a door.

Fig. 2 is a view of the same location outside said door disclosing means for supporting and retaining such a receptacle, the latter being removed.

Fig. 3 is a perspective view of the receptacle alone as seen from another side than appears in Fig. 1.

Fig. 4 is a vertical section of the receptacle when in position outside the door as in Fig. 1, and revealing an automatically locked cover which may be released and opened for depositing a bottle or any other article.

Fig. 5 is a similar view showing the mentioned receptacle cover open and a bottle deposited in the receptacle.

Fig. 6 is also a similar view with the cover closed and no longer releasable from the out-

side, while the house door is open, permitting removal of the bottle from within, or even of the receptacle as a whole.

Throughout the views, the same reference numerals indicate the same or duplicate parts. 55

It has often been a sore nuisance to many householders to find milk or cream stolen after delivery in the morning, and some have supplied their milkmen with house keys to have the bottles delivered inside the house door, 60 in order to avoid such losses. But, this entails the serious drawback that the keys may be lost or fall into the hands of unauthorized parties, and this is worse than the first trouble.

It is therefore proposed herein to have all 65 such articles delivered outside the front door of a house without the necessity of opening said door and yet safely depositing the articles so as to be inaccessible to all but those within the house who can obtain said articles 70 by merely opening the door.

With this and the aforementioned objects in mind, a receptacle, generally indicated by 1 and having a cover 2 hinged at 3, 3, is provided with the two sides 4 and 14, a bottom 75 15 and a front 16. Beneath the hinged portion of the cover 2, the receptacle has an open side indicated at 12. The sides, front and bottom, or 4, 14, 16 and 15, respectively are formed preferably of sheet metal and made 80 into a rigid unit; one side 14 being provided with tongues 11, 11 which are arranged to be inserted in a pair of corresponding loops or straps 9, 9 fastened to the jamb of a house door 7 which is hinged on the post 8 over sill 5. 85

The tongues 11, 11 are directed forward on the receptacle toward the front 16, and the door 7 must first be opened toward the inside 10 or as shown in Fig. 6, when the receptacle is to be placed in position, for the tongues 11, 90 11 may then be disposed behind loops 9, 9 initially, and thereafter engaged therein by pushing the receptacle outward or away from the door 7. The resulting position is shown in Fig. 6, where the open side 12 of the receptacle 95 faces inward into the house and is flush against the door when the latter is closed as shown in some of the other views.

However, when the door is closed for the night, the receptacle is left in position out- 100

side the same, and is, of course empty. Upon the inside of the front 16 is a rigid catch 17 arranged to engage in the slot 18 of a resilient hook or trigger 19 secured to the under-
5 side of cover 2. The cover is normally closed, even when the receptacle is empty. When a person arrives to deliver a milk bottle, say, he need merely pass a finger down through an aperture 13 in the cover and draw back the
10 trigger 19 sufficiently to clear hook 17, when it will be possible to open the cover and de-
posit the bottle in the receptacle. If the cover is then closed down, the trigger or latch 19 will snap into locking engagement with the
15 hook 17, and as the presence of the bottle now makes the latch 19 utterly inaccessible to a finger through aperture 13, the cover is safely locked and the bottle safe against removal. The receptacle can thereafter only be opened
20 by first opening door 7 inwardly and with-
drawing the bottle 20 through open side 12 of the receptacle. It is to be noted when the door 7 is open, the space 21 between the same and the jamb 6 is ample to permit withdrawal
25 of the receptacle and disengagement of its tongues 11, 11 from supporting loops 9, 9 on the jamb. These loops may be placed higher up as desired, so that the receptacle does not rest on sill 5 but is spaced above it. Also, the
30 tongues may be located on side 4 instead of 14 of the receptacle, or both sides may be fur-
nished with them, and there may be more than two tongues on a side. Such modifications are therefore reserved.

35 Having now fully described my invention, I claim:—

In a receptacle of the character described, including a receptacle proper having an open rear side and an open top, there being means
40 to removably retain said receptacle with the open rear side against a door, a cover hinged upon said receptacle and arranged to close down upon said open top, an interior latch means arranged within said receptacle and a
45 corresponding latch member disposed upon the inside of said cover, and means for open-
ing said cover from the exterior when said receptacle is empty including a perforate por-
tion upon said cover through which a finger
50 may be inserted to release said latch means and member from mutual engagement, but which perforate portion is arranged in such position over an object when the latter is de-
posited in said receptacle, that said object
55 will directly block the path from said perfo-
rate portion to said latch means and member within said receptacle and thereby prevent opening said receptacle from without while said deposited object remains within the same.

60 Signed at 132 Nassau Street in the county of New York and State of New York this 4th day of December, A. D. 1929.

ERIC W. JOHNSON.
